HEEL SUPPORTER FOR SHOES

Filed March 8, 1929

Inventor
Louis A. Cook,

By *J. Stanley Burch*
Attorney

UNITED STATES PATENT OFFICE

LOUIS A. COOK, OF AKRON, OHIO

HEEL SUPPORTER FOR SHOES

Application filed March 8, 1929. Serial No. 345,352.

The present invention relates to improvements in shoe attachments and has reference more particularly to an attachment for the inside of the shoe at the heel portion thereof for supporting the heel of the foot whereby to afford maximum comfort to the wearer while walking.

One of the important objects of the present invention is to provide a shoe attachment of the above-mentioned character which possesses a spring-like action underneath the heel of the foot thus eliminating the strain caused each time the heel of the foot strikes the ground.

Another object is to provide an attachment of the above-mentioned character that will not cause any injury to the heel of the foot and which will not tear the heel portion of the stocking or sock, additional means being provided for positively securing the attachment in place within the heel portion of the shoe against movement.

Another object is to provide an attachment of the above-mentioned character which is self-adjusting, the same being at all times efficient and positive in its operation as well as simple in construction, inexpensive, strong and durable and further well adapted for the purposes for which it is designed.

Other objects and advantages of the invention will become apparent from the following description when taken in connection with the accompanying drawing.

In the accompanying drawing wherein like reference characters indicate corresponding parts throughout the same;

Figure 1 is a longitudinal sectional view through the heel portion of a shoe as well as through the attachment embodying my invention.

Figure 2 is a vertical section taken approximately on the line 2-2 of Figure 1.

Figure 3 is a bottom plan view of the heel supporter, per se; and

Figure 4 is a rear edge elevation thereof.

In the drawing wherein for the purpose of illustration is shown the preferred embodiment of my invention, the numeral 1 designates generally my improved shoe supporter

attachment, the same comprising a sheet of spring metal that is cut to conform to the shape of the heel portion of a shoe. Suitable spurs 3 are struck out from the central portion of the spring metal body 2 whereby the same may be rigidly secured in position in the heel portion A of a shoe and in Figure 1 there is clearly illustrated a manner in which these spurs are driven into the heel.

The rounded rear edge portion of the spring metal body 2 is formed with the spaced radial slits 4 whereby to form a series of spring tongues 5, the adjacent spring tongues being disposed in overlapping relation as more clearly shown in Figure 4. It will also be observed that the edge portions of the spring metal body 2 at the sides and rear end portion thereof are slightly curved upwardly so as to be out of contact with the heel portion of the shoe and this feature is clearly shown in Figures 1 and 2 of the drawing.

A covering of leather, felt or other suitable material denoted by the reference character 6 is secured on the upper face of this spring metal body 2 and upon referring to Figure 3 it will be observed that this covering is slightly larger than the spring metal body so that the same extends beyond the respective edges of the body. The fastening means for the covering is shown at 7.

The heel supporter is attached within the heel portion of the shoe in the manner as clearly shown in Figures 1 and 2 and the heel of the foot will engage with the covered spring body and the downward pressure upon the spring tongues 5 caused by the heel of the foot will spread the spring tongues apart and in a downward direction. The spring body will act as a resilient cushion for the heel of the foot whereby to afford maximum comfort to the wearer while walking, running or jumping and the provision of the covering 6 will prevent the spring tongues from coming in contact with the heel of the foot or otherwise injuring the stocking or sock. The simplicity of my device enables the same to be readily and easily positioned in the heel of a shoe and furthermore the spring tongues will render the device or attachment adjustable to various sizes of shoes. The spurs 3 will

absolutely prevent the attachment from moving out of position when placed in the heel portion of the shoe.

A device of this character can be constructed and sold at a very low cost and the same will at all times be positive and efficient in carrying out the purposes for which it is designed.

While I have shown the preferred embodiment of my invention, it is to be understood that minor changes in the size, shape and arrangement of parts may be resorted to without departing from the spirit of the invention or the scope of the appended claim.

15 What I claim is:

An attachment for the inside of the heel portion of a shoe comprising a spring metal body, the rear edge portion of said spring metal body being formed with a series of 20 radial slits forming normally overlapping spring tongues and a heel-engaging covering over the upper face of the spring metal body and the tongues, and attaching spurs struck out from the intermediate portion of the body 25 to secure the same against movement in the heel portion of the shoe, the side and rear edge portions of the spring metal body being normally curved upwardly.

In testimony whereof I affix my signature.

20 LOUIS A. COOK.
